UNITED STATES PATENT OFFICE.

PHILIP SIMONS, OF PEWAMO, MICHIGAN.

HARROW STANDARD AND TOOTH SUPPORT.

Application filed December 13, 1922, Serial No. 606,629. Renewed September 15, 1924.

To all whom it may concern:

Be it known that I, PHILIP SIMONS, a citizen of the United States, residing at Pewamo, in the county of Ionia and State of Michigan, have invented certain new and useful Improvements in Harrow Standards and Tooth Supports, of which the following is a specification.

This invention relates to improvements in harrows, and like implements, and has for one of its objects to provide a device of this character including a standard having a holder carrying a harrow tooth and laterally directed cutters, and means for adjustably coupling the cutters to the standard or disconnecting them therefrom as required.

With these and other objects in view, the invention consists in certain novel features of construction as hereinafter shown and described and then specifically pointed out in the claims, and in the drawings illustrative of the preferred embodiment of the invention.

Figure 1 is a side elevation of one of the improved devices attached to a conventional supporting frame, the frame members being in transverse section.

Fig. 2 is a rear view of one of the improved tooth standards.

Fig. 3 is a plan view of a part of the supporting frame of a conventional harrow with a pair of the improved devices applied.

Fig. 4 is a vertical sectional elevation enlarged.

Fig. 5 is a transverse section on the line 5-5 of Fig. 4 looking in the direction of the arrow.

Fig. 6 is a view similar to Fig. 5 with the cutter carrying bar detached.

Fig. 7 is an enlarged elevation of the double acting clamp member.

Fig. 8 is a view similar to Fig. 1, illustrating a modification in the construction.

Fig. 9 is a rear elevation, and

Fig. 10 is a plan view, of the parts shown in Fig. 8.

Fig. 11 is a detached perspective view of the cutter member as shown in Figs. 8, 9 and 10.

The improved device may be applied to tooth standards of various forms and constructions, but for the purpose of illustration is shown applied to a conventional spring or resilient standard 10 attached at 11 to a conventional beam 12. Any required number of the standards and their attachments

may be employed in each harrow and arranged in the ordinary manner.

Bearing upon the forward face of each standard 10 is a holder device 14 having the edges directed laterally to form flanges 15 to embrace the edges of the standard and thus retain the holder from lateral displacement upon the standard while at the same time permitting adjustment longitudinally of the standard.

Formed upon the holder 14 are guide ribs 16 integral with the flanges 15 and overhanging the holder and the standard 10, as shown in Figures 5 and 6.

Disposed between the guide ribs 16 and the standard 10 is a clamp plate 17, the latter having a central "boss" 18 through which and the body of the plate a threaded aperture is formed to receive a set screw 19.

By this arrangement when the set screw is actuated, strain will be imparted between the standard and the holder to adjustably clamp the latter in position upon the standard.

A shovel 13 is shown riveted at 20 to the lower end of the holder 14, which is the preferable attaching means.

The forward face of the holder 14 is enlarged as shown at 14' with its outer face curved to merge without obstruction into the forward face of the shovel, and thus support the shovel from upward displacement without producing an obstruction to the free passage of the shovel through the earth.

Adapted to bear against the rear face of the standard 10 and between the standard and the clamp plate 17 is a bar 21 having a single laterally directed knife edged cutter 22, as in Figs 1, 2, 3 and 4, or two diverging knife edged cutters 24 as shown in Figs. 8, 9, 10 and 11.

The plate 17 is formed with diametrically disposed opposite enlargements 23, as shown. When the bar 21 is employed two thicknesses of material will be disposed between the ribs 16 and the standard 10, and the plate 17 will be arranged as shown in Figures 2, 3, 4, 5 and 9 with the enlargements 23 between the confronting edges of the ribs 16, but when the bar 21 and its attached cutter 22 are not employed, the plate 17 will be turned one-fourth around to bring the enlargements 23 between the ribs 16 and the standard 10, the enlargements thus taking the place of the bar 21, so that the set screw 19

will operate equally well whether the bar be employed or not.

When thus arranged and the set screw 19 actuated, the three parts 10, 14 and 21 together with their attached portions 13 and 22 will be firmly clamped together and independently adjustable, or the two parts 10 and 14 only may be clamped together with equal facility, as will be obvious and as shown in Figure 6.

In Figures 8, 9, 10 and 11 a modification in the construction of the cutter portion of the device is shown consisting in forming a rearward extension 25 at the lower end of the bar 21, and riveting or otherwise attaching the branching cutter 24 thereto as shown at 26. The portions 21 and 25 are supported or reinforced by a web 27, as shown.

By this means the ground is "worked" at each side of the furrow formed by the shovel 13, whereas with the structure shown in Figures 1, 2, 3 and 4, the ground is "worked" at one side only of the shovel.

The improved device is simple in construction, can be manufactured of any suitable material and of any suitable size.

The preferred embodiment of the invention is disclosed in the drawings and set forth in the specifications, but it will be understood that modifications within the scope of the claims may be made in the construction without departing from the principle of the invention or sacrificing any of its advantages.

Having thus described the invention what is claimed as new is:

1. In a harrow, a tooth standard, a holder adjustably engaging said standard and hav-

ing guide ribs and carrying a harrow tooth, a clamp plate engaged by said guide ribs, and means for applying strain between said guide ribs, plate and standard.

2. In a harrow a tooth standard, a holder adjustably engaging said standard and having guide ribs and carrying a harrow tooth, a clamp plate engaged by said guide ribs, and a set screw operating through said clamp plate to apply strain between said guide ribs, plate and standard.

3. In a harrow a tooth standard, a holder adjustably engaging said standard and having guide ribs and carrying a harrow tooth, a clamp plate engaged by said guide ribs, a bar engaged by said guide ribs and carrying a rearwardly extending cutter member, and means for applying strain between said guide ribs, plate, standard and cutter carrying bar.

4. In a harrow, a tooth standard, a holder adjustably engaging said standard and having guide ribs and carrying a harrow tooth, a clamp plate engaged by said guide ribs and with the diametrically opposite edges increased in thickness, a bar engaged by said guide ribs and carrying a rearwardly extending cutter member, and a set screw operating through said clamp plate and bearing against the bar when the clamp plate is disposed with the thickened portions between the guide ribs, and bearing against the standard when the bar is withdrawn and the thickened portions disposed beneath the guide ribs.

In testimony whereof, I affix my signature hereto.

PHILIP SIMONS.
